FILM EXTRUSION APPARATUS

Arthur O. Russell, Fredericksburg, Va., assignor to American Viscose Corporation, Wilmington, Del., a corporation of Delaware

Application January 23, 1952, Serial No. 267,840

7 Claims. (Cl. 18—15)

This invention relates to apparatus for producing non-fibrous foils, pellicles, films, sheets and like products from film-forming compositions. More particularly, it relates to an improved extrusion device which provides greater adjustability and control of the ultimate thickness of the extruded film.

The manufacture of films, foils and like products is commonly carried out by extruding into a coagulating or regenerating bath a film-forming substance such as viscose from a receptacle or hopper which is provided with slightly separated lips that define an elongated orifice. The thickness and uniformity of the extruded film may be regulated by properly adjusting the width of the orifice or slit. This adjustment from a practical standpoint, however, has been found very difficult since the demands of production often require that the width of the orifice amount to only a fraction of a millimeter. Although various previous improvements have been suggested to overcome this difficulty they have been shown unable to provide sufficient accuracy in controlling the required dimensions of the orifice.

It is a principal object of this invention to provide novel and improved film extrusion apparatus wherein the dimensions of the elongated extrusion orifice may be quickly and accurately adjusted.

It is a further object of this invention to conveniently position the extrusion orifice adjusting means such that it may be easily reached and manipulated.

Other objects and advantages of the invention will become apparent from a description of the embodiments of the invention.

The objects of the invention are attained in general by providing a pair of independent adjusting means for each extrusion orifice. The first adjusting means provides a coarse control of the width of the orifice by slidably adjusting the position of the entire lip member. The second adjusting means provides a more delicate adjustment of the orifice dimension by means of a flexing action of a lip member.

In the accompanying drawing which is illustrative of the invention,

Figure 1 is a front view of a spinning head assembly wherein there is disclosed an improved extrusion lip adjusting means which is designed in accordance with a first embodiment of the invention;

Figure 2 is a section along reference line II—II in Figure 1;

Figure 3 is a top view of the improved spinning head assembly;

Figure 4 is a cross-sectional view of a modified spinning head assembly which is designed in accordance with a second embodiment of the invention;

Figure 5 is an enlarged fragmentary view similar to Figure 2 showing the adjustable lip member in a substantially closed position; and

Figure 6 is a view similar to Figure 5 in which the adjustment achieved has been illustrated in a somewhat exaggerated manner.

2

Referring now more particularly to Figures 1, 2 and 3 of the drawing, the spinning head assembly 3 is rotatably mounted by means of the tubular trunnions 6 in the journals 4 which are positioned at opposite ends of the coagulating vessel or container 5. The hand wheel 7 in Figure 1 of the drawing provides a convenient means for rotatably adjusting the position of the spinning assembly in the journals 4 to control the angular disposition of the spinning orifice in the coagulating vessel or chamber and to invert the assembly for the inspection and maintenance thereof.

The spinning assembly 3 comprises a pair of elongated U-shaped channel members 8 and 9 which are fastened back to back by the bolts 10. Cover plates 11 and 27 extend across the open sides and ends respectively of the channel members 8 and 9 and provide between suitable inlet and discharge means not shown in the drawing, the elongated enclosed chambers 12 and 13 through which may flow a temperature regulating medium such as water, steam or air. The lower portions of the abutting channel members 8 and 9 are preferably recessed as shown in the drawing to form the channel 26 therebetween but it is to be understood that the channel may be formed in any convenient other way such as by inserting a shim between the upper portions of the abutting channel members.

Carried on the underside of the channel members 8 and 9 are the adjustable lip members 14 and 15 which determine the width of the extrusion orifice. Each of the lip members includes in cross-section a lip proper 41 which is formed integrally with a horizontal flange or extension 40 at an angle thereto. As shown in Figures 5 and 6, the extension lies in a horizontal plane whereas the lip proper 41 extends downwardly and obliquely. The extension 40 of lip member 14 is fastened to the lower surface of bearing plate 16 and channel member 8 by a plurality of upwardly extending cap screws 17 which are located along each of its elongated edges. The extension 40 of the lip member 15 is fastened to its respective channel member 9 by a plurality of cap screws 19 which extend upwardly through a plurality of slots 18 in the lip member, through the associated bearing plate 20 and threadedly engage the underside of the channel member. The slots 18 in the lip member 15 permit a transverse sliding adjustment of the lip member as will be described more fully hereinafter.

The opposed angular lips 41 of the orifice defining lip members 14 and 15 are aligned with channel 26 formed between the channel members 8 and 9 and are preferably tapered downwardly toward the extrusion orifice. The upper boundary or wall of the channel 26 between the channel members 8 and 9 is also preferably tapered downwardly from the end of the spinning assembly at which the spinning solution is supplied toward the opposite end thereof. Supporting blocks 28 are bolted to the lower portion of each end of the channel members and extend downwardly therefrom. Each of the supporting blocks carries the bolt means 29 and 30, for removably clamping the end plates 31 across the end extremities of the opposing orifice defining lips. Thus, it is seen that the spinning solution may progress from its source not shown on the drawing through the tubular trunnion 6 along the grooved portion between the channel members and downwardly through the elongated orifice into the coagulating bath.

Each of the lip members 14 and 15 is designed such that it can be independently adjusted to control the dimensions of the extrusion orifice. Lip member 15 may be slidably positioned in slots 18 on cap screws 19 by means of the adjusting screws 21 which threadedly engage the end of extension 40 and extend outwardly therefrom. Supporting bracket member 32 which ex-

tends outwardly and downwardly from the cover plate 11 guides each adjusting screw in slots 33 and cooperates with the adjustable nuts 34 and 35 on the adjusting screws to control the position of the lip member on cap screws 19. This sliding adjustment of lip member 15 readily permits a preliminary coarse adjustment of the orifice dimensions.

The dimensions of the orifice may also be controlled by varying the position of lip member 14. The means which has been devised for controlling the adjustability of lip member 14 includes a plurality of adjusting screws 23 which are fastened along the center of the extension 40 of the elongated lip member and extend upwardly therefrom through the legs of the channel member 8. Supporting bracket member 36 which is mounted on the upper surface of channel member 8 guides the upper portion of the adjusting screws in apertures 37 and cooperates with the adjustable nuts 38 and 39 on the adjusting screws to control the position of the lip proper 41. Thus, variations in the setting of adjusting screw 23 cause a bowing action within the elastic limit of the metal in the mounting portion of the relatively flexible extension between the cap screws 17 and the angular portion simultaneously flexes toward or away from the opposing lip member 15. The adjustment described above results from a bending or flexing of the lip along a minor or transverse axis thereof as opposed to a flexing longitudinally or along the major axis. It has been found that control of this type of flexing action in the lip member provides a very accurate means for making minute adjustments in the width of the orifice. The upper surface of the lip member 14 is preferably undercut at 24 between the axes of the cap screws 17 to provide greater flexibility of the lip member and a greater range of adjustability of the orifice dimensions.

An additional feature of the novel and improved orifice adjusting means of the present invention is to be noted in the ready accessibility of the adjusting means in its conveniently exposed location.

Referring next to Figure 4 of the drawing a second embodiment of the invention is disclosed wherein a pair of adjustably controlled orifices permit the simultaneous extrusion of a like number of non-fibrous films. In this embodiment of the invention the spinning head assembly is divided into two separate chambers 50 and 51 by a downwardly extending inverted Y-shaped partition member 52. The lower portion 61 of the legs of the Y partition form a fixed lip member for each of the extrusion orifices. The opposing lip member 63 of each of the orifices is adjustably mounted by means of the cap screws 54 upon elongated U-shaped channel members 58 which are fastened to the upper portion of the partition member 52 by means of bolts 59. Each of the lip members 63 includes in cross-section a mounting portion and an orifice-defining angular portion which extends downwardly therefrom. The open sides and ends of the channel members are preferably respectively closed by the side plates 53 and end plates not shown in the drawing thereby providing elongated chambers through which a temperature regulating medium may flow as described in the previously described embodiment. As in the previously described embodiment the opposed surfaces of the orifice defining lip members 63, 63 are alined with the chambers 50 and 51 and are preferably tapered downwardly toward the extrusion orifice.

Each of the movable lip members 63 may be slidably positionable in slots 65 on cap screws 54 by means of the adjusting screw 55 which threadedly engages the end of the mounting portion of lip member 63 and extends outwardly therefrom. Supporting bracket member 69 which extends outwardly from the cover plate 53 guides each adjusting screw in slots 70 and cooperates with the adjustable nuts 71 and 72 on the adjusting screws to control the position of the lip member on cap screws 54. This sliding means permits a preliminary coarse

adjustment of the width of each of the orifices. The elongated adjusting screws 57 provide an additional means for varying and controlling the dimensions of the orifice. The elongated adjusting screws are fastened to the center of the mounting portion of each of the elongated lip members 63 between the bolts 54 and extend upwardly therefrom through the legs of channel member 58. Supporting brackets 73 which are mounted on the upper surfaces of channel members 58 guide the upper portion of the adjusting screws in apertures 74 and cooperate with the adjustable nuts 75 and 76 on the adjusting screw to control the position of the lip member. Thus, variations in the setting of the adjusting screw 57 cause a bowing action in the mounting portion of the relatively flexible lip members 63 between the bolts 54 and the angular portion simultaneously flexes toward or away from the corresponding fixed lip member 61. As in the previously disclosed embodiment the upper surface of the lip member is preferably undercut as at 77 to provide greater flexibility of the lip member and a greater range of adjustability of the width of the orifice.

While preferred embodiments of the invention have been described, the description is intended to be illustrative only and it is to be understood that changes and variations may be made without departing from the spirit and scope of the invention as defined by the appended claims.

I claim:

1. Apparatus for defining and controlling the width of an extrusion orifice comprising a pair of opposed lip members, an integrally formed oblique extension on at least one of said lip members, and means for lowering said extension in a transverse plane to control the width of the orifice.
2. Film extrusion apparatus comprising a spinning head assembly having an elongated opening therein, at least one lip secured to the spinning head having a flange extending longitudinally of the spinning head and obliquely to the lip, and means for bending the flange to pivot the lip and thereby control the width of said opening.
3. Film extrusion apparatus comprising a spinning head assembly having an elongated opening therein, at least one lip secured to the spinning head having a flange extending longitudinally of the spinning head and obliquely to the lip, at least one adjusting screw extending through the spinning head and connected to said flange approximately at its center, and means for applying pressure to said screw to flex the flange to adjust the width of the opening.
4. Film extrusion apparatus comprising a spinning head assembly having an elongated opening therein, a pair of opposed orifice defining lip members positioned on the assembly and which partially extend across the width of the opening, a lip proper formed along at least one of the lip members, at least one of the lip members having a flange extending substantially at right angles to said lip proper, and means for bending said flange to adjust the width of the orifice.
5. Apparatus in accordance with claim 4 having a plurality of bolts extending through the head along the length of the flange.
6. Film extrusion apparatus comprising a spinning head assembly having an elongated opening therein, a pair of L-shaped lip members secured to said spinning head, said members having a substantially horizontal extension and a lip proper formed integrally and obliquely therewith, the outer edges of said lips being positioned in close spaced relationship to form an extrusion orifice therebetween, and means for bending the extension of one of said lip members to closely control the width of said orifice.
7. Film extrusion apparatus comprising a spinning head assembly having an elongated opening therein, an L-shaped lip member extending longitudinally of the spin-

ning head, a first fulcrumed edge along the backface of the lip member, a second fulcrumed edge extending along the backface of the lip member in spaced transverse relation to said first edge, and means for bending the lip member between said fulcrums to pivot the outer edge of the lip through an arc centered substantially at one fulcrum.
